John W. Van Cleave of Dayton Ohio.

assignor to

James Green & Co of Dayton Ohio.

Letters Patent No. 591, dated August 16th 1853,

The schedule referred to in these Letters Patent and making part of the same.

To all whom it may concern:

Be it known that I
John W. Van Cleave of Dayton in the County of Montgomery and State of Ohio have designed and produced a new ornamental pattern for a cooking stove and I do hereby declare the following to be a full, clear, and exact description thereof, reference being had to the annexed drawings making part of this specification, and in which,

Fig. 1. represents one side plate of the stove with its included doors,

Fig. 2. is a view of the doors belonging to the opposite side

Fig. 3. shows one of the fire doors - the other one being a counterpart

A bead which borders each side plate, is scolloped in the manner shown at (1), (2) is a section thro this bead,

The doors (b c d e f) are all bordered with a bead (g) whose section is represented at (3) (4 5 6 7 8) represent the ornamentation of the respective door panels, consisting of intermingling scrolls and grasses springing from a rosette as delineated.

What I claim as my invention and desire to secure by Letters Patent is the design and configuration of the ornaments for a cooking stove above described and shown in the accompanying drawings.

In testimony whereof I have hereunto set my hand before two subscribing witnesses,
